UNITED STATES PATENT OFFICE.

LOUIS ZELICK, OF PHILADELPHIA, PENNSYLVANIA.

DESIGN FOR A COMBINED ERASER AND PENCIL-SHARPENER.

59,530.

Specification for Design.

Patented Oct. 25, 1921.

Application filed February 24, 1921. Serial No. 447,619. Term of patent 7 years.

To all whom it may concern:

Be it known that I, LOUIS ZELICK, a citizen of the United States, residing in the city and county of Philadelphia, State of Pennsylvania, have invented a new, original, and ornamental Design for Combined Erasers and Pencil-Sharpener, of which the following is a specification, reference being had to the accompanying drawing, forming part thereof.

Figure 1 is a perspective view of the obverse of a combined eraser and pencil sharpener showing my new design.

Fig. 2 is a perspective view of the reverse thereof.

I claim:

The ornamental design for a combined eraser and pencil sharpener as shown.

LOUIS ZELICK.
